(57) **CLAIM**

The ornamental design for a handpiece adapter for dental irrigation device, as shown and described.

DESCRIPTION

FIG. 1 is a rear isometric view of a handpiece adapter for dental irrigation device;

FIG. 2 is a front isometric view thereof;

FIG. 3 is a side view thereof, where the opposing side, top, and bottom view is identical to the side perspective view; FIG. 4 is top-to-bottom section view thereof, taken along line 4-4 of FIG. 3;

FIG. 5 is a rear view thereof; and,

FIG. 6 is a front view thereof.

The broken line shown in the drawings is included for the purpose of illustrating portions of the handpiece adapter for dental irrigation device and forms no part of the claimed design.
